UNITED STATES PATENT OFFICE.

THOMAS M. GRANT, OF SAN FRANCISCO, CALIFORNIA.

KNIT SHIRT.

SPECIFICATION forming part of Letters Patent No. 268,093, dated November 28, 1882.

Application filed August 24, 1882. (No model.)

To all whom it may concern:

Be it known that I, THOMAS M. GRANT, of the city and county of San Francisco, State of California, have invented an Improvement in 5 Knit Shirts; and I hereby declare the following to be a full, clear, and exact description thereof.

My invention relates to certain improvements in knitted shirts, such as are employed 10 for underwear; and it consists in forming that part of the shirt above the waist in two thicknesses united at top and bottom, but separate at intermediate points.

Referring to the accompanying drawings 15 for a more complete explanation of my invention, Figure 1 is a view of my shirt. Fig. 2 is a vertical section on the line 5 6, Fig. 1. Fig. 3 is a plan taken on the line 1 2, Fig. 1. Fig. 4 is a plan taken on the line 3 4, Fig. 1.

20 In the use of the ordinary knitted shirts for underwear they often become wet by perspiration, induced by labor or exertion of any kind, and if the wearer is subsequently exposed to a draft or cools off suddenly various results 25 may follow.

My invention contemplates the construction of a shirt, which, while it is all in one piece, shall be double above the waist and around 30 the loins and pulmonary organs, so as to provide an exterior dry thickness outside of that which lies next to the body and is liable to become wet by perspiration.

A is the body of my shirt, which is knit by machinery in the usual manner. B is an ex-

terior or interior thickness, knit in the same 35 manner and made long enough to extend from the throat to below the loins. I have shown this secondary or supplemental thickness or re-enforcement as placed on the inside of the main shirt and united to it at C, being fastened off by the usual machinery for such work. The joining at the neck is made in the same manner, these being the only points where the two are united. Between these points the two parts A and B are free and 40 independent, and may carry a layer of air in their meshes and between them. Whenever the inner shirt becomes exposed to perspiration it will absorb it and retain it, while the outer thickness and the layer of warm air between 45 will protect the wearer from cold drafts of air and the chill which would necessarily follow any sudden depression of the temperature of the body.

Having thus described my invention, what 50 I claim as new, and desire to secure by Letters Patent, is—

As a new article of manufacture, a knitted shirt having double sides A and B united at C and D and entirely surrounding the body 55 between those points, substantially as herein described.

In witness whereof I hereunto set my hand.

THOS. M. GRANT.
